UNITED STATES PATENT OFFICE.

VICTOR HENDERSON, OF ROSENDALE, MINNESOTA.

DESIGN FOR A COTTER-PIN.

SPECIFICATION forming part of Design No. 34,938, dated August 13, 1901.

Application filed July 13, 1901. Serial No. 68,270. Term of patent 3½ years.

To all whom it may concern:

Be it known that I, VICTOR HENDERSON, a citizen of the United States, residing at and whose post-office address is Rosendale, in the county of Meeker and State of Minnesota, have invented a new and useful Design for Cotter-Pins, of which the following is a specification.

This invention relates to a new and useful design for a cotter-pin; and the novelty resides in the peculiar construction and arrangement, as will be fully described hereinafter and illustrated in the accompanying drawing, in which the figure is a side elevation of a cotter-pin illustrated in accordance with my invention.

Referring now to the drawing, 1 designates an elongated cylindrical pin tapering at one end and at its other end provided with an approximately O-shaped loop 2. At a point

opposite the pin 1, at its juncture with the loop 2, is a U-shaped crimp 3, the free end of which is formed in a straight bar 4, parallel with the pin 1, the end of side bar 4 being bent downwardly at 5 to a point immediately adjacent the pin 1 and then terminating in an outwardly-projecting extension 6 at a tangent to the pin 1.

Having thus fully described my invention, what I claim, and desire to secure by Letters Patent, is—

The design for a cotter-pin, substantially as herein shown and described.

In testimony whereof I affix my signature in presence of two witnesses.

VICTOR HENDERSON.
